UNITED STATES PATENT OFFICE.

JAMES H. FRENCH AND SAMUEL T. SIMPSON, OF CAMBRIDGE, MASSACHUSETTS.

SALES-BOOK.

Specification of Letters Patent. Patented Apr. 11, 1916.

1,178,793.

Application filed September 29, 1914. Serial No. 864,050.

To all whom it may concern:

Be it known that we, JAMES H. FRENCH, a subject of King George V of England, and SAMUEL T. SIMPSON, a citizen of the United States, both residing at Cambridge, in the county of Middlesex and State of Massachusetts, have invented new and useful Improvements in Sales-Books, of which the following is a specification.

10 Our invention relates to manifolding devices for hand or counter uses generally, but more especially to sales or order books and to novel means for positioning and retaining original and duplicate order blanks, as also 15 an interposed transfer sheet or sheets, in proper operative relation upon a suitable baseboard or book back.

The invention has for an object to provide a book of the character indicated which is 20 at once durable, efficient and of simple construction; adapted to be supported upon one hand of a user while with the other he may conveniently make entries and remove or manipulate the pages as occasion requires.

25 Another object is to provide a book capable of use either with or without inclosing covers, and devoid of exterior projections which might otherwise interfere with placing it in the pocket, or cause injury to the 30 hands of a user.

35 Another object of the present invention is to provide efficient means for readily positioning, replacing and holding in position for use additional order blanks, preferably in the well known perforated pad or tablet form, and for similarly securing carbon or transfer sheets at one side thereof in a manner to render them self positioning at all 40 times.

45 Other objects and advantages will be apparent to persons skilled in the art to which these improvements relate, and without further enumeration the invention will now be particularly described and pointed out in the claims following.

50 In the accompanying drawings which form part of this application for Letters Patent and whereon corresponding numerals refer to like parts in the several views: Fig. 50 ure 1 is a perspective view of the invention in its preferred form of construction, an order pad being here shown in position for use with the uppermost page curled back to disclose a transfer sheet beneath. Fig. 2 is 55 a detail view also in perspective illustrating a metallic base with end and side clamps

both connected integrally with said base. Fig. 3 is a sectional view taken transversely and centrally through Fig. 1. Fig. 4 is a fragmentary view showing in side elevation 60 the end of an order-blank retaining-clamp. Fig. 5 is also a fragmentary view showing in longitudinal section one end of the side or transfer-sheet retaining-clamp closed. Fig. 6 illustrates in side elevation a modified form of transfer-sheet retaining-clamp 65 in wide open position, and Fig. 7 is an end view of the clamp illustrated by Fig. 5, but in this instance shown closed.

Essentially and broadly stated this invention resides in a holder for order blanks and the like comprising a unitary rigid base plate having integral upturned flanges at one side and one end thereof serving primarily to position order blanks in uniform 75 alignment upon said base plate, and secondarily to assist in retaining them in operative position.

The invention further resides in means for detachably securing order blanks to one of 80 said flanges, and means for similarly securing a transfer sheet or sheets to the other of said flanges for manifolding purposes.

Reference being had to the drawings and numerals thereon, 1 indicates a book back of 85 any suitable material such as card board, either cloth or leather bound, and connected at one end by a flexible hinge 2, to a corresponding book cover 3. As a matter of convenience the latter is provided in its binding, at top and bottom edges, with pockets 4, 4, adapted to receive opposite ends of a 90 flexible and removable memoranda card 5. None of the book binding features aforesaid, however, constitute any part of the 95 present invention except as employed in the general combination, and such features may therefore be of any well known form of construction and material or materials.

Resting upon the inner surface of the book 100 back 1 and secured in place by suitable over-laying binding material 6 is a base plate 7 105 preferably of sheet metal solid and of rectangular form as best shown by Fig. 2 of the drawings. This element, however, may, if preferred, be of skeleton outline, and of various forms without in the least departing from the spirit of the invention or detracting from its usefulness as will later appear. At its upper end the base plate 7 is bent upwardly at right angles throughout its entire 110 width, thus forming the integral relatively-

- fixed hinge member 8, of an order pad retaining-clamp, which is completed by a movable member 9 hinged horizontally as at 10, spring-pressed as at 11, having a serrated edge 12, and a centrally disposed thumb lift 13 as clearly shown by Figs. 1 and 2. In like manner at its left side said base plate 7 is provided with an integral upstanding flange 14 constituting the relatively fixed 10 member of a transfer sheet retaining-clamp as best shown by Fig. 2 of the drawings. Throughout practically its length the said flange 14 is slightly corrugated as at 15 in its longitudinal center, and vertically secured to its lower end by a hinge 16, is a clamping bar 17 corresponding in shape with said flange 14, like it corrugated centrally and longitudinally as at 18 (see Fig. 3), and terminating in a latch 19 adapted 15 to when closed to spring over a suitable vertical keeper 20 at the upper end of the said flange 14.

By way of modification the side transfer sheet retaining-clamp may be formed substantially as shown by Figs. 6 and 7 of the drawings, wherein the integral flange 14^a is angled up from base plate 7, to receive clamping bar 17^a, the latter having slightly projecting ends, which bar is connected by a 20 horizontal hinge of well known construction, and is spring pressed as at c to normally close the clamping members as shown by Fig. 7.

The construction first above described, however, is obviously the preferred form of our invention, but we do not consider that we are limited to such, on the contrary various changes in the structural arrangement of parts, materials employed, and proportions shown, may be made and substituted without in the least departing from the principles of operation, and to all such we lay claim the same as if herein shown and described.

45 The use and operation of our invention will now be briefly set forth as follows: A sheet of transfer paper 21 of suitable size, having first been inserted beneath the lower edge of clamping bar 17 is securely crimped in position by contact with the nesting corrugations 15 and 18 when the said bar is closed and latched at 20 as shown by Fig. 5. The transfer sheet then being held in a vertical position a supply of order blanks, or an 50 order pad such as 22, is introduced into the holder, beneath clamping member 9 and there secured as shown by Fig. 1. During this operation it is obvious that the integral upstanding flanges 8 and 14 insure a proper 55 positioning of the order blanks, and consequent alinement at all times of the characters thereon. The uppermost order blank being now temporarily turned back, transfer sheet 21 is laid, or automatically falls into 60 position, upon the second or duplicate order

blank in pad 22 the uppermost, or original blank, then being replaced, as in Fig. 1 whereupon the device is in condition for use. When thus arranged and positioned it will be noted that the present invention is capable of all uses to which such devices are ordinarily subjected, and in addition particular attention is directed to the fact that clamping bar 17 is practically locked in its closed, or clamped position by engagement 70 of one side of the order pad 22, as best shown by Figs. 1, 3 and cannot be opened until there is occasion to introduce another pad 22, or until the one in use is first removed from its clamping jaw 9. Moreover, 75 as the supply of order blanks and duplicates are exhausted in the usual process of recording and manifolding orders, transfer sheet 21 automatically adapts itself to this condition by virtue of the fact that it feeds from 80 below its clamping bar 17, and as a consequence is always flat lying beneath the uppermost order blank, and therefore unlikely to become torn or separated from its fastening means.

In the usual course both the original and duplicate order blanks are removed from the holder after each entry, one being intended for the purchaser or customer, and one for the dealer, but obviously their removal is 85 not essential to the use and operation of the present invention. On the contrary they may if preferred be permitted to accumulate in the holder, and in such event it will be noted that the transfer sheet 21, feeding 100 from below the bar 17 as aforesaid, conveniently serves the additional function of a book marker, indicating at a glance where the next order should be entered.

Having thus described our invention what 105 we now claim and desire to secure by Letters Patent is:

1. A metallic holder for order blanks having a tablet base and upwardly projecting integral flanges upon adjacent sides thereof adapted to prevent movement of blanks in the direction of said flanges, in combination with means for detachably securing order blanks in stacked alinement to one of said flanges, and a clamping bar pivotally connected to the other of said flanges and movable in a plane parallel with the surface of said base for detachably securing a transfer sheet in operative position.

2. A metallic holder for order blanks having a tablet base and upwardly projecting integral flanges upon adjacent sides thereof adapted to prevent longitudinal and transverse movement of blanks in the direction of said flanges, in combination with clamping 120 means for detachably securing order blanks in stacked alinement to one of said flanges, and a clamping bar hinged to the other of said flanges and movable in a plane parallel 125 with the surface of said base for detachably 130

securing a transfer sheet to the said last mentioned flange.

3. A metallic holder for order blanks having a tablet base and upwardly projecting integral flanges upon adjacent edges thereof adapted to prevent longitudinal and transverse movement of blanks in the direction of said flanges, in combination with means for detachably securing order blanks in stacked alignment to one of said flanges, a clamping bar hinged to the other of said flanges at one end thereof and movable in a plane parallel with the surface of said base

for detachably securing a transfer sheet to the last mentioned flange, and a latch upon 15 said clamping bar for interlocking with its supporting flange.

In testimony whereof we have hereunto set our hands in presence of two subscribing witnesses.

JAMES H. FRENCH.
SAMUEL T. SIMPSON.
